CLAIM

The ornamental design for a caliper body of disk brake for vehicle, as shown and described.

DESCRIPTION

FIG. 1 is a front view of a first embodiment of a caliper body of disk brake for vehicle;

FIG. 2 is a rear view thereof;

FIG. 3 is a top plan view thereof;

FIG. 4 is a bottom plan view thereof;

FIG. 5 is a right side elevation view thereof;

FIG. 6 is a left side elevation view thereof;

FIG. 7 is a perspective view thereof;

FIG. 8 is a front view of a second embodiment of a caliper body of disk brake for vehicle;

FIG. 9 is a rear view thereof;

FIG. 10 is a top plan view thereof;

FIG. 11 is a bottom plan view thereof;

FIG. 12 is a right side elevation view thereof;

FIG. 13 is a left side elevation view thereof; and,

FIG. 14 is a perspective view thereof.

The broken lines in the drawings illustrate portions of the caliper body of disk brake for vehicle that form no part of the claimed design.

1 Claim, 14 Drawing Sheets
